United States Patent Office.

A. C. SPENCER, OF BRIDGEPORT, CONNECTICUT, ASSIGNOR TO HIMSELF,
E. B. JONES, AND WILLIAM H. FRENCH, OF SAME PLACE.

Letters Patent No. 79,511, dated June 30, 1868.

COMBINATION OF WOOD AND PAPER FOR CABINET PURPOSES.

See Schedule referred to in these Letters Patent and making part of the same.

TO ALL WHOM IT MAY CONCERN:

Be it known that I, A. C. SPENCER, of Bridgeport, in the county of Fairfield, and State of Connecticut, have invented a new Process for Combining Wood and Paper for Cabinet Purposes; and I do hereby declare the following, when taken in connection with the accompanying drawing, and the letters of reference marked thereon, to be a full, clear, and exact description of the same, and which said drawing constitutes part of this specification, and represents a sectional view of a piece of combined wood and paper.

The object of this invention is to positively prevent the shrinking which is unavoidable in cabinet-work, however thoroughly the wood may be seasoned; and is particularly adapted to sewing-machine-table tops, as, by its construction, it acts as a non-conductor, and the noise of the machine at work thereon is completely deadened. The necessity for a sewing-machine-table top which should possess this quality, together with the non-shrinking or warping, has suggested this invention, which consists in combining several sheets or layers of paper or pasteboard, glued, gummed, or otherwise secured solidly together, and covered upon their surface with a veneer of wood.

In order to the clear understanding of my invention, I will fully describe the same as illustrated in the accompanying drawings.

I will first describe for sewing-machine-table tops. The centre part, A, is formed by combining one or more thicknesses of paper or pasteboard, gluing or sticking the one upon the other until of the thickness required. The upper and under surfaces, a and b, I cover with a thin veneer of any desirable wood, and having dressed the edges, I glue thereto the moulded edge B, and the table-top is complete.

This combination of paper acts as a non-conductor of sound, and is, to a certain extent, elastic, so that no jar or vibration is communicated from the machine through the table to the floor, as is unavoidable in solid wood tops; and under whatever reasonable circumstances the table may be placed, the top will not warp or twist out of the proper shape.

This invention is alike applicable for panelling in cabinet-work, and for such uses possesses the quality of not shrinking, a quality which it is impossible to give to solid wood panels.

Another and equally important use for this invention is, for forming circular or irregular forms, as paper may be piled upon the desired curve, and in such form the several layers glued together cannot, by any possibility, lose the form thus given them; and covered by the wood, as described, a circle or irregular form is produced, which, as it cannot shrink, will not break or crack from the adjacent parts, as solid wood almost invariably will do.

Other uses for this process might be suggested, but these are sufficient to illustrate its importance and value.

Having thus fully described my invention, what I claim as new and useful, and desire to secure by Letters Patent, is—

The herein-described process for combining wood and paper for cabinet and other purposes.
